STAMP APPLYING MECHANISM

Dean A. Marshall, 13389 23rd Place, Golden, Colo.
Filed Apr. 15, 1963, Ser. No. 273,021
3 Claims. (Cl. 156—531)

This invention relates to apparatus for automatically applying a stamp from a stamp roll to a piece of material; more particularly, the invention relates to a stamp applying mechanism in which plunger action serves to feed stamps through the apparatus.

A major disadvantage of prior automatic stamp applying mechanisms is their complexity. A further disadvantage of prior art devices is the fact that the severing mechanism for separating a single stamp from a stamp roll was not reliable and often did not provide for dependable separation along the perforation of the stamp roll. Also, mechanisms in prior art devices for properly aligning the stamp roll in the feeder mechanism and for properly orienting the stamp at the end of the roll for correct placement on the envelope were extremely complicated and expensive.

Accordingly, it is an object of this invention to provide a highly simplified mechanism for the automatic application of a stamp from a stamp roll to an envelope. It is another object of this invention to provide stamp severing mechanism in a stamp applying apparatus which is entirely reliable for cleanly separating a stamp at a perforated area in the stamp roll. It is still another object of this invention to provide mechanism in a stamp applying apparatus for accurate lateral alignment of the stamp roll in the feeding mechanism and for providing simplified support mechanism for properly orienting the stamp to be applied to the envelope.

The invention is best described with reference to the accompanying drawings in which like parts are represented by like numerals and in which,

FIG. 1 is a top plan view of the stamp applying apparatus of the invention;

FIG. 2 is a side view of the apparatus of the invention;

FIG. 3 is a partial sectional view of the feeding and stamping mechanism of the apparatus of the invention;

FIG. 4 is a sectional view taken on the line 4—4 of FIG. 3 looking in the direction of the arrows;

FIG. 5 is a sectional view taken on the line 5—5 of FIG. 3 looking in the direction of the arrows;

FIG. 6 is a sectional view taken on the line 6—6 of FIG. 2;

FIG. 7 is a sectional view taken on the line 7—7 of FIG. 6 looking in the direction of the arrows;

FIG. 8 is a sectional view taken on line 8—8 of FIG. 5 looking in the direction of the arrows; and

FIG. 9 is a sectional view taken on the line 9—9 of FIG. 4.

Referring to FIG. 1, there is shown a base 10 provided with an upright back plate 12 upon which the elements of the stamp applying mechanism are supported.

A reservoir 14 for containing moistening fluid is supported on back plate 12 by means of support peg 16. A spindle 18 for supporting a roll of stamps is supported on the back plate 12 by means of screw 20 or other suitable means. Located between the reservoir 14 and the spindle 18 is a stamping mechanism represented generally at 22 and a support mechanism represented generally at 24.

Reference is now made to the other figures of the drawings, and particularly FIGURES 2 and 3, for a more detailed description of the structure and operation of the stamp applying mechanism of the invention.

Referring to FIGS. 2 and 3, the mechanism for moistening an envelope 28 (represented by dotted lines) is provided by fibrous pad 30 mounted in the reservoir which

2

is contacted as an envelope is forced to the right immediately beneath it (FIG. 2) to allow moisture to wet the envelope in the area which receives the stamp. Other suitable means for moistening an envelope in the proper place may, of course, be used.

5 A plunger 32 is housed in plunger housing 33 which is supported by screws or otherwise on the back plate 12. This housing as best seen in FIG. 3 is provided with an internal neck 34 to support the plunger in an upright position and through which it slides. The plunger housing 33 is provided with an elongated side 36 adjacent the reservoir. It will be noted that in FIG. 2 the position of the plunger and the elements which it carries, along with the envelope and a stamp in position for application thereon, 10 are all shown in dotted lines. The positioning lever arm 38 to be described below is also shown in dotted lines in its alternate position in this figure. The plunger 32 is spring biased into upward position by spring 38 biased between the underside of knob 40 and the top of the housing 33.

15 Mounted inside the housing and conforming with the internal dimensions thereof is a stamping block 42 which is attached to the end of the plunger at 44 by mating screw threads or otherwise. The stamping block 42 is provided with a guard plate 46 which limits the upper movement of the plunger and, accordingly, the stamping block 42. Two legs 41 on the front of the stamping block 42 provide for a space between its bottom and the base 10 when it is seated. Constructed integrally with the stamping block 42 or with the guard plate 46 is a row 20 of three-dimensional teeth 48 for a purpose to be described later. For applying pressure to a stamp to tear it from a roll of stamps and to seal it to the envelope through action of the plunger, a pressure pad 50, preferably of fibrous material, is pivotally attached to the bottom of stamping block 42. The pressure pad 50 is mounted on a backing plate 52, preferably of thin metal, which is pivotally attached to the bottom of stamping block 42 by means of a pin 54 extending through the stamping block to which it is attached by a swivel connection (not shown specifically) of any suitable means. The elongated side 36 serves as a guide for plunger 32 and stamping block 42 as the plunger is moved back and forth.

25 A stationary jaw 56 is secured to base 10 by means of screw 58 or other suitable means. Constructed integrally with the stationary jaw is a stationary row of teeth 60 arranged in line vertically with teeth 48 to mesh with them. A slot 61 is provided in teeth 60 for a purpose which will be explained later. These teeth are also of three-dimensional construction for a reason which will be explained later. It will be seen that the teeth 48 in conjunction with stamping block 42 with which they move form a movable jaw which cooperates with stationary jaw 56 to mesh the two rows of teeth together when the plunger is moved to its downward position as shown in dotted lines in FIG. 2.

30 The three-dimensional taper or bevel of the teeth comprising the two rows of teeth 48 and 60 is shown in FIGS. 4 and 6. This is a highly important feature of the device in that it permits meshing of the teeth in two planes to sever a stamp along perforations of the roll even though the two rows of teeth may be slightly out of alignment. It is this feature which insures the severing of a stamp each time the plunger is moved to the closed position.

35 The support or feed mechanism, represented generally at 24, for supporting a row of stamps 62 in position so that top row of teeth 48 will be aligned with a transverse row of perforations of the stamp roll, will now be described in detail. As shown in FIGS. 2 and 3, a base plate 64 is mounted by means of flange 66 to back plate 12 in secure fashion by screws or otherwise. As shown in FIG.

7, a top view of the base plate, this plate is provided with two pairs of opposed slots 68 for a purpose to be described later. A row of dots or marks 70 is provided for alignment purposes as will be described hereinafter. The dots are spaced apart a distance equal to the distance between perforations in the transverse rows of perforations in the stamp roll.

The top plate 72, mounted for cooperation with the base plate 64 to properly support a row of stamps for the severing action of the plunger and plunger head or stamping block 42, constitutes the other main element of the support mechanism. As best seen in FIG. 6, the top plate 72 is provided with a vertical stud 73 threadably engaged with lateral adjusting screw 74 mounted on back plate 12 and provided with set screw 75. Top plate 72 may thus be laterally adjusted by turning of knurled head 76. As shown in FIG. 8, a bottom view of the top plate 72, this plate is provided with guide pins 77 which cooperate with the slots 68 in the base plate 64 to provide for lateral adjustment of the top plate 72 with respect to the base plate. As seen in FIGS. 5 and 8, the top plate 72 is provided with opposed vertical adjustment slots 78. When the top plate 72 is in position, the slots 78 are directly over threaded holes, not shown, extending through base plate 64. In order to provide for vertical adjustment of the distance between the top plate and base plate, and thereby provide for adjustment of the pressure on the stamp roll between the plates, spring loaded vertical adjustment screws 79 are threadably engaged at their ends with the threaded holes in base plate 64 and are spring loaded by means of screw springs 80 which are biased between the heads of screws 79 and guide plate 82. It is readily seen that by vertical adjustment of the screws 79 the pressure between the top plate and base plate can be adjusted. As seen in FIG. 8, the top plate 72 is provided with a peep slot 84 through which the row of dots 70 can be observed for alignment of the perforations laterally to conform with the dots. As seen in FIG. 6, the top plate 72 is provided with internal slots 86 which extend horizontally in the direction of travel of the stamp roll. The purpose of these slots is to provide space when needed for excess area of stamps which happen to be larger than stamps used in conventional stamp rolls.

A guide plate 82 provided with a downwardly extending flange overlapping the ends of plates 64 and 72 is mounted on the top of plate 72 by means of screws 79 and springs 80 as previously described. The purpose of the guide plate is to guide the stamp downwardly and to cooperate with lever 88 to take the reverse crimp out of the stamp to insure that it is maintained in a flat orientation for pressing on the envelope. The end of the guide plate also serves to prevent reverse travel of the succeeding stamp due to the motion of guard 46 as the plunger is raised after the stamping action. The device will operate satisfactorily without the guide plate but this element improves its operation.

For properly aligning a stamp as it is fed beneath the pressure pad 50 so that the upper tooth 48 engages the row of perforations, a positioning lever 88 is supported by screw 90 (FIG. 6) on peg 92 which is attached to back plate 12 by a screw 93 or other convenient means. The positioning lever 88 is spring biased into upward position so that its end contacts the bottom of the first stamp, by means of biasing spring 94 mounted over peg 92 and having one end attached to or supported against movement by base plate 64 and the other end attached to the lever arm 88. In this position the lever prevents curling of the stamp and cooperates with guide plate 82 to hold the stamp in a flat position. It will be seen from FIG. 2 that the lever arm 88 is positioned so that its top edge will be contacted by the top row of teeth 48 as the plunger 32 is moved to the closed position to move the lever to its dotted line position as shown in FIG. 2, with its end nesting in slot 61. The lever can be constructed and arranged to seat against the teeth themselves and the slot 61 dispensed with.

The entire assembly of the stamp applying mechanism may be provided with a suitable removable cover if desired. A container 96 for moistening fluid and an envelope guide 98 and wetting pad may be provided in the base for moistening the envelope flap for sealing.

The operation of the stamp applying apparatus of the invention is described as follows. The stamp roll referred to herein, and which is used in the stamp applying apparatus of the invention, is the conventional roll of postage stamps sold by U.S. Post Offices and comprises a roll of some 100 or more stamps joined together by paper linkages which are provided with transverse rows of perforations providing for separation of the stamps by tearing along the perforations.

A roll of stamps is loaded in the machine by placing it over spindle 18 and threading the end of the roll between base plate 64 and top plate 72 until the first stamp extends beneath pressure pad 50 and the first row of perforations is lined up with the upper row of teeth 48. The pressure on the stamp roll between top plate and base plate is adjusted by means of vertical pressure adjustment screws 79 until the required pressure for proper feeding of the stamp roll is reached. It is important that the stamp roll be properly aligned laterally and this is achieved by laterally adjusting top plate 72 by means of lateral adjustment screw 74 until the dots 70 can be observed through the perforations in the stamp roll and peep slot 84. The apparatus is now ready for applying a stamp to an envelope.

An envelope 28 is moved into position as shown in FIG. 2, and as it moves into position contacts pad 30 to moisten the area to which the stamp is to be applied. With the envelope and the first stamp in position, the plunger 32 is pressed downward to the closed position. As the plunger is moved downward, the upper row of teeth 48 will be inserted in the transverse perforations succeeding the first stamp to move the roll down to the severing position where the first stamp is severed from the roll by means of the meshing teeth. It is thus seen that the feeding movement of the stamp roll is accomplished by the plunger action. As the plunger with the stamping block 42 moves downward, the lever arm 88 will be pressed downward to the retracted position as shown in FIG. 2, meanwhile being in contact at all times with the second stamp in the roll after it has guided the first stamp into position under the pad 50. At the closed position of the plunger the lever arm 88 will be pressing the second stamp against the guard plate 46 to hold it there for the next action of the plunger.

As the stamping block 42 moves down with the plunger, the pressure pad 50 is maintained in its angled position by the manner in which it is mounted on the bottom of stamping block 42 so that its forward end contacts the stamp first, smooths it out, clears it from the teeth 60 and further extends it to the proper position before it presses it into sealed position. It is thus seen that the lever 88 and the pressure pad 50 cooperate to properly align the stamp as it is moved to its required position on the envelope and that the lever 88 also functions to hold the next stamp in the roll in proper position to prevent it from curling while the first stamp is being sealed on the envelope. As the plunger is retracted the lever arm 88 retracts to position the second stamp in the proper position under the stamp pad and prevent it from curling. It is important that the pressure pad be maintained at an angle so that its front edge strikes the stamp first, and that the positioning lever 88 be properly positioned with respect to the upper row of teeth and the guard plate 46 to properly perform its function. Also of importance is the amount of vertical pressure exerted on the stamp roll between the base plate 64 and top plate 72, and the proper lateral alignment of the stamp roll. All of these factors, coupled with the three-dimensional meshing teeth contribute to the reliability of the apparatus in insuring the proper positioning of each stamp and sever-

ance thereof as it is applied to the envelope or other article.

It will be seen from the above description of the construction and operation of the stamp applying apparatus of the invention, that the invention provides an extremely simplified device which is readily adaptable to simple manufacturing techniques. The device is highly dependable in providing for accurate positioning of a stamp on an article and in providing for severance of each stamp at the proper time. It provides simplified mechanism for adjusting vertical pressure on the stamp roll in the feed mechanism and in providing for lateral adjustment of the stamp roll therein. It further provides a dependable and simplified arrangement of elements for properly positioning a stamp on an article and for insuring that the succeeding stamp is in position for proper alignment and sealing on an envelope. A significant advantage of the invention is the fact that an automatically operating device is provided through a highly simplified construction.

It is therefore to be understood that various modifications and changes may be made in the construction and arrangement of parts of the present invention without departing from the spirit and scope thereof as defined by the appended claims.

What is claimed is:

1. Apparatus for removing a stamp from a stamp roll and sealing it to an article comprising: means for supporting a roll of said stamps; feed support means for supporting in feeding relationship a stamp at the end of said roll, said feed support means comprising a base plate and a top plate laterally and vertically adjustable with respect to each other, said base plate being provided with reference means serving as a guide for lateral adjustment of said roll in said feed support means and said top plate being provided with an opening through which said roll can be viewed for aid in lateral adjustment thereof; a stationary jaw having at least one row of three dimensional teeth thereon; a movable jaw having a row of three dimensional teeth thereon which coact with the teeth of the stationary jaw to sever completely said stamp from said roll; and plunger means to which said movable jaw is attached, for affixing the teeth thereof in the area between said stamp and the succeeding stamp to feed the stamp to the proper position, for meshing said teeth together to sever completely said stamp from the roll and for pressing said stamp on said article.

2. Apparatus for sealing a stamp from a stamp roll having a row of perforations between stamps to an envelope comprising: a base; an upright back plate sup-

ported on said base; a reservoir for holding moistening fluid supported near one end of said back plate with means in its bottom for application of moisture to said envelope in the area to receive a stamp; a spindle member supported near the other end of said back plate for supporting a roll of stamps with the roll surrounding the spindle; a feed support mechanism between said reservoir and spindle comprising a base plate supported at a slight angle to the horizontal and a top plate cooperating with the base plate to support said stamp roll between them; means for vertically adjusting the distance between said top and base plates; means for lateral adjustment of the plates with respect to each other; a lever arm supported on said back plate below said feed mechanism and spring biased into the upward position to contact the bottom of said stamp to position it; a stationary jaw on the top of said base beneath said lever and having a first row of three dimensional teeth thereon; a plunger housing supported on said back plate between said reservoir and said feed mechanism having a wall adjacent said reservoir extending near said base with its lower end serving as a guide for an envelope being stamped; a plunger mounted in said housing and spring biased into the upward position; a stamping block on the bottom of said plunger for pressing a stamp on said envelope; a pivotal pad on the bottom of said stamping block for contacting said stamp; a second row of three dimensional teeth adapted to coact with said first row of teeth located on the side of said stamping block adjacent said feed support mechanism and positioned to contact said lever on downward movement of the block and to enter said row of perforations to sever said stamp from said roll as one of said rows of teeth move past the other said row upon downward movement of said plunger.

3. The apparatus of claim 2 in which a guide plate is mounted on the top of said top plate and a slot is provided in said stationary jaw for receiving the end of said lever arm in its downward position.
